UNITED STATES PATENT OFFICE.

THOMAS HERBIG, OF HORN BROOK, CALIFORNIA.

STARTING DEVICE FOR EXPLOSIVE-ENGINES.

1,096,716.

Specification of Letters Patent.

Patented May 12, 1914.

Application filed April 18, 1911. Serial No. 621,797.

To all whom it may concern:

Be it known that I, THOMAS HERBIG, a citizen of the United States, residing at Hornbrook, in the county of Siskiyou and State of California, have invented new and useful Improvements in Starting Devices for Explosive-Engines, of which the following is a specification.

This invention relates to starting devices for explosive engines and has for one of its objects the provision of a device of this character which will be simple in construction, easy to manipulate, and efficient and positive in operation.

Another object of the present invention is to provide a starting device for explosive engines wherein by a simple operation, a priming or initial charge of the motive fluid is prepared, forced under pressure into the engine cylinders, and ignited within the cylinders, thereby giving the engine its initial impulse and enabling it to pick up its own cycle of operation.

A further object of this invention is to provide a starting device for internal combustion engines for motor vehicles which is supported by and upon the engine, under the hood of the vehicle, and forward of the dash whereby an operator may start the engine with ease and convenience and without the necessity of leaving his seat.

With the above and other objects in view, the invention consists in the construction, combination and arrangement of parts hereinafter set forth in and falling within the scope of the claims.

In the accompanying drawings: Figure 1 is a side elevation of my improved starting device applied to the engine of a motor vehicle, the hood and dash being shown in section. Fig. 2 is a section on the line 2—2 of Fig. 1. Fig. 3 is an enlarged longitudinal section illustrating the mixing and pressure chamber and its connections with the air pump and engine cylinders. Fig. 4 is a perspective view of the air pump illustrating the valve operating and sparking device. Fig. 5 is a longitudinal sectional view of the supply valve and; Fig. 6 is a perspective view of one of the brackets for securing my improved starting device to the engine cylinders.

Referring to the drawings, wherein similar reference numerals designate like parts throughout the several views, 1 indicates the dashboard, 2 the hood, 3 the radiator and 4 the gasoline engine of a motor vehicle.

My improved starting device is secured to the engine cylinders by means of brackets 6 each comprising a vertical portion 48 fastened to the cylinders at 49, by means of bolts, and terminating at its upper end in a forked arm 50 provided with bolt holes aligning with openings in the valve casing 10 of the starting device, whereby the brackets may be rigidly secured to the casing.

My improved starting device comprehends a gasoline tank or reservoir 7, an air pump 8, a combined cut-off and distributing valve 9, and a valve casing 10 provided with passages 17 for conveying the motive fluid to a combined mixing and pressure chamber 12, wherein the motive fluid is prepared and forced into the engine cylinder through suitable conduits. The tank or reservoir 7 is provided with the usual filling opening 13 and outlet conduit 14 said conduit leading to the valve 9 in the casing 10. The valve 9 comprises a tapering body formed with a chamber 15, one end of said chamber being closed by a wall formed integral with the body and having a squared portion 46, projecting therefrom for the purpose of receiving a valve operating lever 43. The opposite end of the chamber 15 is closed by a plug 44, said plug being screw threaded into the body of the valve to permit of its removal when it is desired to gain access to the interior of the chamber 15 for cleaning or other purposes. The outlet conduit 14 of the tank 7 communicates with valve 9 through a port 45, said port being normally open to the conduit. Outlet ports 16, are formed in the valve, at an angle between 45 and 90 degrees to the port 45, the number of said ports depending upon the number of cylinders of which the engine is composed, four cylinders being shown in the drawing. The valve casing 10 is provided with passages 17 leading from the valve 9 to a combined mixing and pressure chamber 12. The chamber 18 is located at the bottom of the valve casing 10 and extends longitudinally

thereof and is provided with discharge nozzles in the form of nipples 19 connected by means of packing nuts 20 to the conduits 21. The conduits 21 are composed of short 5 lengths of piping and lead to the engine cylinders and are connected thereto by means of the spark plugs. The spark plugs for this purpose constitute a combined sparking and priming plug of any well known structure. The conduits 21 are provided with 10 check valves 22 adapted to open under pressure of the mixture being forced into the cylinders and to prevent such mixture from backing into the conduits upon the explosion 15 of such mixture.

Brackets 23 are formed on the upper surface of the casing 10 and are adapted to receive and securely hold the air pump 8. The pump comprises the usual cylinder 24, 20 piston 25 and piston rod 26 which rod is provided with an operating handle 28. The cylinder is provided with front and rear heads 29 and 30 respectively. The rear cylinder head 30 in addition to the usual air 25 intake port 32, is provided with a stationary electric contact block 34, insulated from said head and connected with the ignition mechanism at any suitable point by means of a conductor 35. A port 41 formed in said cylinder head 30 leads from the interior of the pump cylinder to the chamber 12 and communicates therewith by means of a short section of piping 42, whereby the air from the pump cylinder may be forced into the 30 chamber 12, for the purpose of mixing the air with the gasoline and forcing the same into the engine cylinders through the conduits 21. The front head 29 is provided with a laterally projecting lug 31 adapted 35 to carry a combined valve and spark operating rod 36. The said rod 36 is rigidly connected to the operating rod of the pump piston for simultaneous operation therewith. This connection is made through the medium of an arm 51 preferably formed integral with the rod 36, and rigidly secured to the pump operating rod by means of a set screw 37. In its normal position the pump piston is midway the ends of the cylinder 40 and is held in such position by means of a spring 38. The said spring 38 encircles the operating rod 27, and one end thereof engages the cylinder head 29, and the opposite end engages the arm 51 of the rod 36. The 45 rear end of the rod 36 carries an electric contact block 39 adapted to contact with the block on the rear cylinder head 30 and thereby make and break the electric circuit leading to the spark plugs. The said block 39 is adjustable along the length of the rod 36 and is held in its adjusted position by means of a set screw 40, the purpose of this adjustment is to enable the sparking apparatus 50 to be operated at any desirable point relative to the length of stroke of the piston 25.

A slot 42 is formed in the rod 36 for the reception of the operating lever 43 of the valve 9, whereby upon the operation of the pump, the rod 36 is moved with the pump rod which imparts movement to the valve 70 9. The bore of the valve casing 10 is of a tapering contour to correspond with the formation of the valve. The valve is secured in said casing by means of a cap nut 45 and spring 46 said spring having ball-bearing connection with said cap nut as indicated at 47. This method of securing the valve in place provides means for taking up any wear on the valve or casing due to the oscillating motion of the valve, 80 and at the same time enables the valve to operate freely within the casing. A portion of the piston rod 26 and the operating handle 28 project through the dash 1 of the vehicle, whereby the device is placed within 85 convenient reach of the operator.

The operation of my improved starting device may be stated to be as follows:—By the force of gravity the gasoline in the tank 7 is discharged into the chamber 15 of the 90 valve 9 through the conduit 14 and port 45 of said valve, said port in its normal position being in communication with the conduit the chamber 15 is therefore charged with gasoline. Upon pulling the handle 28 of the piston air is drawn into the cylinder through the port 32, and the rod 36 is simultaneously operated with and by the piston to cause the rear wall of the slot 42 to engage the valve lever 43 causing 95 said lever to assume the position indicated in dotted lines in Fig. 1, in which position the valve 9 is out of communication with the gasoline tank and the ports 16 of said valve casing whereby the gasoline contained in the chamber 15 of the valve is discharged through said passages 17 into the chamber 18. On the return stroke of the piston the valve 9 is cut off from communication with the passages 17, by means of the front wall of said slot 42 engaging the valve lever 43, and the air which was previously drawn into the pump cylinder is discharged into the chamber 18 through the conduit 42, 100 whereby the gasoline within the chamber 18 is caused to mix with the inrushing air and by the action of the same is forced through the conduit 21 into the engine cylinders. When the pump piston has completed its stroke the contact block 39, carried on the lever 36, engages the block 34, carried by the rear head of the pump cylinder, and thereby completes the circuit to the 105 spark plugs, causing an explosion of the mixture within the cylinders and thereby starting the engine. Upon releasing the pump handle 28, the spring 38 causes the pump to assume its normal position, breaking the circuit at the contact blocks and 110 115 120 125 130

placing the device in position for another operation.

I do not limit myself to the exact details of construction as herein set forth as various changes may be made within the scope of the claims, and without departing from the spirit of the invention or sacrificing any of the advantages thereof.

Having thus described my invention, 10 what I claim and desire to secure by Letters Patent is:—

1. A starting device for explosive engines, comprising a reservoir, a combined mixing and pressure chamber communicating with the reservoir and with the engine cylinder, a valve controlling the communication between the reservoir and said chamber, a pump having communication with said chamber, and means carried by said 20 pump for operating said valve.

2. A starting device for explosive engines, comprising a tank, a chamber communicating with said tank and with the engine cylinders, a valve controlling the communication between the tank and said chamber, a pump cylinder communicating with said chamber, a piston in said cylinder and means for operating said piston and means connected with said last named means for 30 operating said valve.

3. A starting device for explosive engines, comprising a tank, a chamber communicating with said tank, a valve controlling the communication between said tank and said chamber, a pump having communication with said chamber, and means for operating said pump and said valve, whereby the motive fluid is delivered to the said chamber prepared therein and forced under 40 pressure into the engine cylinders.

4. A starting device for explosive engines comprising a tank, a chamber communicating with said tank, a valve controlling the communication between the tank and said chamber, a pump cylinder communicating with said chamber, a contact block carried by said cylinder, a piston mounted in said cylinder, means for operating said piston and means connected with said last 50 named means for operating said valve and completing the electric circuit through said contact block, whereby the motive fluid is delivered to the engine cylinders and ignited therein for the purpose of giving the 55 engine its initial impulse.

5. A starting device for explosive engines comprising a reservoir, a combined mixing and pressure chamber communicating with said reservoir and with the engine cylinders, a valve controlling the communication between the reservoir and said chamber, a pump cylinder provided at one end with an air intake port, a valve controlling said port, a conduit communicating with 60 said end of the pump cylinder and with

said chamber, a piston mounted within the cylinder, means by which the piston may be operated to draw air into the cylinder and discharge it therefrom into said chamber, a connection between said first named 70 valve and said means, said connection adapted to open the valve during the intake stroke of the piston to permit motive fluid to pass from the reservoir to said chamber, and to close said valve on the compression 75 stroke of the piston to cut off communication between the reservoir and said chamber, the motive fluid in said chamber being mixed with air and forced into the engine cylinders during the compression stroke of 80 the piston.

6. A starting device for explosive engines, comprising a reservoir, a combined mixing and pressure chamber communicating with said reservoir and with the engine cylinders, 85 a valve controlling the communication between the reservoir and said chamber, a pump cylinder communicating with said chamber and having a valved air intake port, a piston mounted in said cylinder, operating means for said piston, a valve operating rod carried by said means, said rod being formed with a slot, a lever carried by said valve adapted to enter said slot, one wall of said slot adapted to engage said 90 lever during the intake stroke of the piston to permit motive fluid to pass from the reservoir to said chamber, the other wall of said slot adapted to close said valve on the compression stroke of the piston to cut 95 off communication between the reservoir and said chamber, the motive fluid in said chamber being prepared and forced into the engine cylinder during the compression stroke of the piston. 100

7. A starting device for explosive engines, comprising a reservoir, a combined mixing and pressure chamber communicating with said reservoir and with the engine cylinders, a valve controlling the communication between the reservoir and said chamber, a pump cylinder provided at one end with a valved air inlet, a conduit connecting said end of the cylinder with the said chamber, an electric contact block carried by said 110 end of the cylinder, a piston mounted in said cylinder means for operating said piston, a combined valve and spark operating rod carried by said means, an adjustable contact block carried by said rod and said rod 115 adapted to open the valve during the intake stroke of the piston to permit motive fluid to pass from the reservoir to said chamber, and to close said valve on the compression stroke of the piston to cut off communication 120 between the reservoir and said chamber, the motive fluid in said chamber being mixed with air forced into the engine cylinders during the compression stroke of the piston the completion of said compression 125 130

stroke causing the said blocks to contact with one another whereby the mixture in the cylinders is ignited.

8. In a starting device for explosive engines, the combination with a pump, of a combined cut-off and distributing valve, means associated with said pump for operating said valve, a combined mixing and pressure chamber communicating with said valve, the motive fluid being prepared in said chamber and distributed therefrom to the engine.

9. A starting device for explosive engines, comprising a reservoir, a combined mixing and pressure chamber communicating with said reservoir and with the engine cylinders, a valve controlling the communication between the reservoir and said chamber, a casing surrounding said valve, passages formed in said casing said passages forming the means of communication between said valve and said chamber, upon the operation of the valve in one direction.

10. A starting device for explosive engines, comprising a tank, a pump, a combined mixing and pressure chamber communicating with said tank and with the engine cylinders, and in communication with said pump, a valve controlling the communication between the tank and said chamber and means actuated by the pump for operating said valve.

11. A starting device for explosive engines comprising a tank adapted to contain motive fluid, a chamber in communication with said tank and with the engine cylinders, means for compressing the motive fluid in said chamber and delivering it therefrom to the engine cylinders, means connected with said last-named means whereby the motive fluid may be ignited within said cylinders, and means for adjusting the ignition of the mixture within the cylinders relatively to the first-named means.

12. A starting device for explosive engines comprising a tank adapted to contain a motive fluid, a chamber communicating with said tank and with the engine cylinders, means for compressing the motive fluid within the said chamber and delivering it therefrom to the engine cylinders, means associated with the last-named means whereby the motive fluid may be ignited within the cylinders, and means for adjusting the ignition of the mixture within the cylinders relatively to the first-named means.

13. A starting device for explosive engines comprising a tank adapted to contain motive fluid, a chamber communicating with said tank and with the engine cylinders, means for compressing the motive fluid in said chamber and delivering it therefrom to the engine cylinders, means associated with

the last-named means to ignite the motive fluid within the cylinders, and means for adjusting the last-named means relatively to the operation of the first-named means to control the ignition of the fluid within the cylinder.

14. The combination with an explosive engine, of a starting device including a tank adapted to contain a fluid, a chamber in communication with said tank and with the cylinders of the engine, means for preparing and compressing the motive fluid in said chamber and delivering it therefrom to the engine cylinders, means connected with the last-named means to ignite the fluid within the cylinders, and means for timing the ignition of the mixture with respect to the operation of the first-named means.

15. A starting device for explosive engines comprising a reservoir, a combined mixing and pressure chamber communicating with the reservoir and with the engine cylinder, means controlling the communication between said reservoir and chamber, a pump communicating with said chamber, and means associated with said pump and operable therefrom for operating the first-named means.

16. A starting device for explosive engines comprising a reservoir, a chamber communicating with said reservoir and with the engine cylinder, means controlling the communication between said reservoir and chamber, a pump communicating with said chamber, a piston in said cylinder, means for operating the piston, and means associated with the last-named means and operable therefrom to actuate the first-named means.

17. In a starting device for explosive engines, a reservoir adapted to contain a fluid, a combined pressure and mixing chamber in communication with the reservoir and with the engine cylinders, means controlling the communication between said reservoir and chamber, means for preparing and compressing the fluid in said chamber, and means for operating the first and last means to establish communication between the reservoir and the chamber and to prepare and compress the fluid in said chamber respectively.

18. In a starting device for explosive engines, a reservoir adapted to contain a motive fluid, a chamber in communication with said reservoir, a pump in communication with said chamber, a valve controlling the communication between said reservoir and chamber, a sparking device, and means operable to actuate the pump, sparking device and valve simultaneously.

19. In a starting device for explosive engines, a reservoir adapted to contain a fluid, a combined pressure and mixing chamber in communication with the cylinders, means

controlling the communication between said reservoir and chamber, means for preparing and compressing the fluid in said chamber, and means for operating the last 5 means to prepare and compress the fluid in said chamber and deliver such fluid therefrom to the engine cylinders.

In testimony whereof I affix my signature in presence of two witnesses.

THOMAS HERBIG.
